Primary Examiner — Sandra Snapp(74) *Attorney, Agent, or Firm* — Hunton & Williams LLP(57) **CLAIM**

I claim the ornamental design for a parking meter housing,
as shown and described.

DESCRIPTION

FIG. 1 is a front perspective view from above of the claimed
design;

FIG. 2 is a front view of FIG. 1;

FIG. 3 is a rear view of FIG. 1;

FIG. 4 is a right side view of FIG. 1;

FIG. 5 is a left side view of FIG. 1;

FIG. 6 is a top plan view of FIG. 1;

FIG. 7 is a bottom plan view of FIG. 1;

FIG. 8 is a second, front perspective view from above of
FIG. 1;

FIG. 9 is a rear perspective view from above of FIG. 1; and,
FIG. 10 is a front perspective view from below of FIG. 1.
The additional structure depicted by broken lines in FIG. 8
has been shown for the purpose of illustrating environment
that forms no part of the claimed design.
